T. C. KRINGS.
COMBINED FOLDING IRONING TABLE AND SLEEVE BOARD.
APPLICATION FILED APR. 5, 1908.

933,568.

Patented Sept. 7, 1909.

UNITED STATES PATENT OFFICE.

THEODORE C. KRINGS, OF CLARINDA, IOWA.

COMBINED FOLDING IRONING-TABLE AND SLEEVE-BOARD.

933,568.

Specification of Letters Patent. Patented Sept. 7, 1909.

Application filed April 5, 1909. Serial No. 488,042.

To all whom it may concern:

Be it known that I, THEODORE C. KRINGS, a citizen of the United States, residing at Clarinda, in the county of Page and State 5 of Iowa, have invented certain new and useful Improvements in a Combined Folding Ironing-Table and Sleeve-Board; and I do declare the following to be a full, clear, and exact description of the invention, such as 10 will enable others skilled in the art to which it appertains to make and use the same.

This invention relates to improvements in combined folding ironing table and sleeve board.

15 The object of the invention is to provide an ironing table of this character which may be quickly and easily folded into compact form.

20 A further object is to provide an ironing table having an improved construction and arrangement of sleeve board which may be swung down to an out of the way position when not in use, thus providing an unobtrusive ironing surface for the board.

25 With the foregoing and other objects in view, the invention consists of certain novel features of construction, combination and arrangement of parts, as will be more fully described and particularly pointed out in 30 the appended claims.

In the accompanying drawings, Figure 1 is a side view of the ironing table showing the sleeve board in operative position in full 35 lines and in inoperative position in dotted lines; Fig. 2 is a top plan view; Fig. 3 is an end elevation; Fig. 4 is an edge or side view, with the parts in folded position.

Referring more particularly to the drawings, 1 denotes the board or table to the 40 underside of which is secured and suitably spaced apart, a pair of longitudinally disposed cleats 2 which are firmly held in position by corner braces 3. On the outer sides of the cleats 2, midway between their ends 45 are secured filling blocks 4 having inclined or obliquely disposed outer surfaces, the purpose of which will hereinafter appear.

Between the cleats 2 and adjacent to one 50 end of the same is pivotally secured the upper end of a longitudinally disposed center supporting leg 5 which projects in the direction of the opposite end of the board or table and in an inclined position, as shown. In the upper edge of the leg 5 is formed a 55 series of notches 6 with one of which is adapted to be engaged the lower end of a

supporting bail 7, the upper ends of which are pivotally engaged with the cleats 2, as shown at 8.

Pivots connected to the inclined faces 60 of the spacing blocks 4 are rear supporting legs 9 which, by reason of their engagement with the inclined sides of the blocks 4, will diverge or spread toward their lower ends, as clearly shown in Fig. 3 of the drawings. 65 Also pivotally secured to the inclined surfaces of the blocks 4 as at 11 are leg adjusting blocks 10 of polygonal shape or provided with a series of angular edges which are at different distances from the center of pivotal 70 connection of the blocks. The legs 9 are adapted to be engaged with one of the angular edges of the block 10, said edges limiting the outward movement of the legs and holding the same in operative position. By 75 turning the block 10 to bring the different edges of the same into position to be engaged by the legs 9, said legs will be held at a greater or less inclination, thus providing for the supporting of the board or table at 80 different elevations. The adjustment of the board on the leg 5 being provided for by the engagement of the supporting bail 7 with one or the other of the notches 6 in the leg, so that said board or table may be maintained in a horizontal position at different 85 elevations.

Arranged above one end of the board or table is a sleeve board 12, the outer end of which is pivotally connected to the upper 90 ends of attaching bars 13, which are pivotally connected at their lower ends to the outer sides of the adjacent ends of the cleats 2. The bars 13 are adapted to engage slots or notches 14 formed in the adjacent end of 95 the board or table 1 when the sleeve board is in an operative position.

Hingedly connected, in any suitable manner, to the lower side of the sleeve board 12, adjacent to its outer end, is a supporting 100 bail 15, the lower end of which is adapted to be engaged with the upper side of the board 1 and with the adjacent edges of the bars 13, as shown, thereby supporting the sleeve board in an operative position above 105 the ironing board or table 1. By thus attaching the sleeve board 12 to the ironing board, said sleeve board may be readily swung back and down around the end of the ironing board or table to an out of the way 110 position, as shown in dotted lines in Fig. 1 of the drawings.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as defined in the appended claims.

Having thus described my invention, what I claim is:

1. In a device of the character described, 15 an ironing board or table, an inclined center leg pivotally connected at its upper end to the underside of the table, means pivoted to the table to adjustably support the table on said leg, a pair of rear supporting legs 20 pivotally connected at their upper end to the underside of the table, and means pivoted to opposite sides of the table for supporting the rear supporting legs at various inclinations to support the table at different elevations.

2. In a device of the character described, 30 an ironing board or table, a pair of longitudinally disposed cleats secured to the underside of the table, an inclined center leg pivotally connected to said cleats, means to adjustably support the table on said leg, inclined spacing blocks secured to said cleats, rear supporting legs pivotally connected to said blocks, whereby said legs are spread or 35 diverged toward their lower ends, polygonal leg engaging blocks pivoted to said spacing blocks whereby said blocks may be adjusted to hold said legs at various angles, and thereby support the board or table at different elevations.

3. In a device of the character described,

an ironing board or table, longitudinally disposed cleats secured to the underside of the table, spacing blocks secured to said cleats, said blocks having inclined outer surfaces, 45 a center supporting leg pivotally connected at its upper end to said cleats, said leg having formed therein a series of notches, a supporting bail pivotally connected to the board and adapted to be engaged with one 50 or the other of said notches to support the board in horizontal position on said legs, a pair of rear supporting legs pivotally connected at their upper ends to the inclined faces of said spacing blocks, a polygonal leg 55 holding block having angular edges arranged at different distances from its center of pivotal connection, whereby the block may be turned to bring its various edges into position to be engaged by said legs 60 thereby holding the same at various inclinations to support the board at different elevations.

4. In a device of the class described, an ironing board or table, a pair of longitudinal cleats secured to the bottom of the table, an inclined center leg pivoted between said cleats, means pivoted to the table to support the latter upon said center leg, spacing blocks arranged at the outer face of the 70 cleats and a pair of rear supporting legs pivoted to said blocks for supporting the table, the outer faces of the spacing blocks being inclined outwardly whereby the rear supporting legs are held at an angle.

In testimony whereof I have hereunto set my hand in presence of two subscribing witnesses.

THEODORE C. KRINGS.

Witnesses:

JAMES H. MILLEN,
STELLA LISLE TURNER.
